MINIATURE FISH TANK

Harry A. Wisotsky, Brooklyn, N.Y.

Application July 21, 1958, Serial No. 51,866

Term of patent 3½ years

(Cl. D91—2)

Fig. 1 is a front elevational view of a miniature fish tank showing my new design;

Fig. 2 is a right side elevational view; and

Fig. 3 is a back view thereof.

The side not shown is substantially the same as the side shown in Fig. 2.

I claim:

The ornamental design for a miniature fish tank, substantially as shown and described.
